UNITED STATES PATENT OFFICE.

SYDNEY BURGESS AND WALTER J. BURGESS, OF HAMILTON, ONTARIO, CANADA.

SHOCK ABSORBER.

Application filed September 18, 1922. Serial No. 589,024.

To all whom it may concern:

Be it known that SYDNEY BURGESS and WALTER J. BURGESS, both subjects of the King of Great Britain, and residing at Hamilton, in the county of Wentworth and Province of Ontario, Canada, have invented certain new and useful Improvements in Shock Absorbers, of which the following is a specification.

10 Our invention relates to improvements in shock absorbers for motor vehicles and more in particular to shock absorbers for use in connection with full-elliptic, semi-elliptic, and three-quarter-elliptic springs.

15 The invention consists essentially of a rocker arm pivotally connected intermediately of its ends to the lower road spring unit and extending horizontally rearwardly and inclined forwardly, the rear end of said 20 arm being pivotally connected to a horse-shoe shaped shackle whose opposite end is pivotally connected to the upper spring unit or the vehicle frame, the forward end of the 25 said arm being connected to a tensioned rod whose opposite end is indirectly connected to said frame at an advanced point.

The principal object of the invention is to 30 provide a simple and effective shock absorber of such novel construction as to afford the maximum of efficiency at an appreciatively less cost than any device previously produced for a similar purpose.

A further object is to provide a device of 35 this character which may be installed as an accessory on the majority of well known and popular makes of motor vehicles, within a short time, with little labor, and without the mechanic having to have acquired previous skill or instruction on installation.

40 These, together with other objects, may be attained by the combination, construction and arrangement of parts as will be herein-after more fully described, illustrated in the accompanying drawing, and pointed out in the claims hereunto appended.

Referring to the drawing:

Figure 1 is a side elevation of the present invention in connection with the more frequently used semi-elliptic spring and vehicle frame extending to a point in vertical alignment with the end of the road spring.

50 Figure 2 is a plan view of the figure shown in Figure 1.

Figure 3 is a side elevation of the inven-

tion as used in connection with a three-quarter or full-elliptic road spring.

55 Figure 4 is a sectional side detailed view of the piston rod and cylinder assembly.

Figure 5 is a detailed side elevation of the frame connection assembly for the front shock absorber; and,

Figure 6 is a plan view of the assembly shown in Figure 5.

Similar reference characters refer to similar parts throughout the several views.

65 In Figures 1 and 2, A indicates the frame of the motor vehicle, and B one of the cross members. C indicates the lower road spring unit in both Figures 1 and 3, and in Figure 3 D indicates the upper road spring member 70 of a full or semi-elliptic spring.

Supplanting the usual spring shackles connecting the ends of the lower and upper road spring units, or connecting the lower spring with the frame, are horse-shoe shaped 75 shackles 2 and a rocker arm. This rocker arm comprises a cross member 3 upon which are formed two rear arms 4 substantially horizontally disposed and parallel with the road spring. The free ends of the arms 4 80 are bifurcated as indicated at 5. To the inner end of the cross member 3 is connected integrally a laterally offset arm 6 which is disposed forwardly at an incline and together with the arms 4 forms an obtusely 85 angular body at elevation. The free end of the arm 6 is also bifurcated as indicated at 7. The arms 4 are connected near the cross member 3 by the bolt 8 which passes intermediate through the shackle bolt eye 9 of 90 the spring unit C. The bolt 8 forms a rocker pivot.

The horse-shoe shaped shackles 2 are 95 embraced at one end in the bifurcations 5 on the arms 4 and are pivoted thereto by the bolts 10, and the opposite ends of said shackles are pivotally connected to the end of the frame A by the bolt 11, as shown in Figures 1 and 2, or to the upper spring unit D, as shown in Figure 3, by the shackle bolt 100 12 passing through the shackle bolt eye 12.

105 The bifurcation 7 embraces and is pivotally connected to the free end of the piston rod 13, to whose opposite end is secured the piston 14 adapted to reciprocate in the cylinder 15. Into the tapped ends of this cylinder are threaded the end plates 16 and 17, the ends of the cylinder then being peened

and pinned against these plates as indicated at 18 and 19 respectively.

The end plate 16 is provided with integral lugs 20 which embrace a link 21 to which it is pivotally secured by the bolt 22. The opposite end of the link 21 is rigidly secured to a fixed member of the vehicle frame A, which may be the cross member B for example.

10 The piston rod 13 is slidably mounted in a sleeve 23 cored into the end plate 17 and extending a substantial distance into the interior of the cylinder 15 to provide ample bearing for the said piston rod.

15 Interposed in the cylinder 15 between the piston 14 and the end plate 17 is a spirally coiled expansion spring 24 normally expanded and tensioning the piston 14 against the end plate 16, and consequently normally 20 tensioning the rocker arm in the direction indicated on the drawing by arrows.

The device shown in the drawing is intended for the rear road spring of vehicles, but may be adapted for the front road 25 spring without any changes except the manner in which the cylinder is connected to the frame, there being an absence of cross members near the forward end of a standard motor vehicle. A bracket 25 secured to the frame A may be substituted for the link 21, and to which the cylinder is secured in the same manner in which it is secured to the link.

There has thus been provided a simple 30 and effective device for the purpose specified and the class described.

Having now fully described our invention, what we claim and desire to secure by Letters Patent, is:—

40 1. In a device of the class described, the combination with a vehicle frame and a road spring, of a rocker axially connected to the end of said spring and comprising twin arms extending normally in a horizontally disposed position connected by a cross member and a laterally offset arm inclined in the opposite direction forming together with the twin arms an obtusely angular body in elevation, substantially horse-shoe shaped shackles linking the free ends of the twin arms with said frame, and means connecting the free end of the offset arm to the frame at a point remote from the

first mentioned frame connection, and tensioned to retard the axial movement of said rocker under varying load.

2. In a device of the class described, the combination with a vehicle frame and opposed road spring units, of a rocker axially connected to the end of one spring unit and comprising twin arms extending normally in a horizontally disposed position connected by a cross member and a laterally offset arm inclined in the opposite direction forming together with the twin arms an obtusely angular body in elevation, substantially horse-shoe shaped shackles linking the free ends of said twin arms with the other road spring unit, and means connecting the free end of said offset arm to the frame remote from the point where said shackles are linked to the second road spring unit, and tensioned to retard the axial movement of said rocker under varying load.

3. In a device of the class described, the combination with a vehicle frame and a road spring, of a rocker axially connected to the end of said spring and comprising twin arms extending normally in a horizontally disposed position connected by a cross member and a laterally offset arm inclined in the opposite direction forming together with the twin arms an obtusely angular body in elevation, substantially horse-shoe shaped shackles linking the free ends of the twin arms with said frame, a cylinder pivotally connected to the frame at a point remote from the first mentioned frame connection, a piston and piston rod reciprocally mounted in said cylinder, said piston rod being pivotally connected to the free end of said offset arm and normally disposed at an angle therewith, means within said cylinder for tensioning said piston and piston rod relatively closer to the point of connection between the cylinder and frame to retard the axial movement of said rocker under varying load.

In testimony whereof we have affixed our signatures.

SYDNEY BURGESS.
WALTER J. BURGESS.
